United States Patent Office.

MATTHEW TOWNSEND, OF CANTON, MASSACHUSETTS.

Design No. 4,388, dated October 4, 1870.

DESIGN FOR DRESS-GOODS.

The Schedule referred to in these Letters Patent and making part of the same.

To all whom it may concern:

Be it known that I, MATTHEW TOWNSEND, of Canton, in the county of Norfolk and State of Massachusetts, have invented and produced a new and original Design for Dress-Goods, of which the following is a specification.

The nature of my design is fully represented in the accompanying photographic illustration, to which reference is made.

The cloth or fabric is represented at A.

A darker band or border at B.

The fabric again at C.

A double row of light-colored knots D, made on the dark fringe E.

I claim as my invention—

The design for dress-goods, as shown.

MATTHEW TOWNSEND. [L. S.]
